UNITED STATES PATENT OFFICE.

JOHN FRANKLIN MACINDOE, OF PHILADELPHIA, PENNSYLVANIA.

FLEXIBLE LUBRICANT-CONTAINER.

1,379,197.

Specification of Letters Patent. Patented May 24, 1921.

Application filed November 29, 1919. Serial No. 341,525.

To all whom it may concern:

Be it known that JOHN FRANKLIN MACINDOE, a citizen of the United States, residing at Philadelphia, in the county of Philadelphia and State of Pennsylvania, has invented certain new and useful Improvements in Flexible Lubricant-Containers, of which the following is a specification.

This invention relates to improvements in 10 grease or other lubricant cans, tubes or containers.

An object of the invention is to provide a neat, compact and economical container whereby grease, or other semi-solid lubricant, can be forced or fed therefrom into grease cups.

With this and other objects in view my invention consists of the new and novel construction and combination described in 20 the specifications attached hereto and made a part hereof, and illustrated in the accompanying drawings, wherein:—

Figure 1 is a front elevational view of the preferred form of container, the upper portion thereof being in section, illustrating a threaded stopper or plug in the outlet thereof;

Fig. 2 is likewise a front elevational view with the upper portion in section, illustrating an unthreaded cap or plug in position in the outlet thereof;

Fig. 3 is also a front elevational view, partly in section, the container being inverted, illustrating same applied to the inlet of the conventional type of grease cup and feeding grease therein, and

Fig. 4 is a similar view to Fig. 3, illustrating the grease cup filled.

Like reference characters refer to like 40 parts throughout the drawings.

Referring to the drawings in detail the character A denotes a tube or container for grease or other semi-solid lubricant, constructed of a suitable flexible material, preferably lead or a kindred metal, or it may be made of paper or fiber, providing such paper or fiber be of the proper consistency to insure an oil tight tube.

The said tube A is formed with a rounded 50 or convex head B. An outlet or opening C is provided in the said tube A by turning the convex head B inwardly and downwardly on each side, substantially in the center thereof, as illustrated particularly in 55 Figs. 1 and 2 of the drawings. The portions of the head thus turned inwardly,

designated by the characters D, form flanges and may be female threaded as in Fig. 1, or plain as in Fig. 2.

A stopper or cap plug E, male threaded to 60 engage the female threads on the flanges D is provided to seal the outlet C, or a cork or plug F of any suitable material, without threads, may be utilized for the same purpose. The said flanges or turned in portions 65 D need only extend downwardly in the tube A to a sufficient depth to accommodate the threads of the stopper E. If the form of stopper F is used there is ample space for it to extend below the depth of said flanges 70 if required.

In Figs. 3 and 4 I have illustrated the container A in position to force or feed lubricant into the conventional type of a compression grease cup G, secured to a bearing H.

To realize the full utility of the container in this connection the said grease cup G should not have a diameter greater than the diameter of the head B of the container A, 80 which as before said is convex in form, although it can be made flat, or nearly so.

In operation: The stopper is removed from the container and the convex head B thereof enters the open end of the grease cup G proportionately as the diameter of the cup relates to the said convex head B. The end of said tube A acts as a stop valve and when sufficient lubricant is in the tube the pressure created thereby is instantly felt and pressure 85 on the tube is relaxed and the said tube is thus kept in contact with the open end of the cup G. In removing same from this contact the said tube A is given a rotary or wiping movement in order to leave a smooth, concaved surface to the lubricant in the cup, instead of being withdrawn straight out, as is the present custom, whereby an indefinite and uneven amount of lubricant is left in the cup G. The head B being convex in 90 form prevents the flooding of the cup G which so universally occurs when these cups are filled by the means now in vogue, and further it provides the space I for the plunger of the usual type of spring compression 100 grease cup. This plunger space is necessary and most manufacturers of grease cups call attention to the filling of the cups in some such statement as "do not fill cups level full as space must be left for the plunger," etc. 105

The present method of filling grease cups is inconvenient, soils the hands, wastes lubri-

cant and endangers the contents of the tube or container when the lid is off or the stopper out during the cup filling process. With the method now in use it is necessary to use either the finger, a piece of wood conveniently shaped, a knife blade or other metal substitute in order to transfer the grease from the container to the cup during which time the contents of the container are endangered from sand or other particles of grit or dirt being blown therein or otherwise gaining access thereto.

Grease to be thus used is usually put up in one, two, five and up to ten pound cans for average automobile use requiring an outlay proportionately to the quantity obtained and this outlay represents grease and container cost, but does not include the convenience, cleanliness and economy which are obtained by the use of the present device.

Another feature of my device is that it may be applied to a grease cup in any position that such cup may occupy on an automobile, aeroplane, motor boat and the like.

With the large number of grease cups on the

average automobile and the various positions in which they are placed thereon, this is a feature of considerable novelty.

It is understood that various modifications may be made to the form of container described, not involving invention, which are to be included within the scope of the herein-after appended claim.

Having thus described my invention what I claim as new and desire to secure by Letters Patent is:

A collapsible lubricant container, for use in filling grease cups, provided with a convex head engageable with the top of a grease cup and adapted to project thereinto so as to form a smooth surface to the lubricant filled into said cup and to leave a plunger space at the top of said cup free of lubricant, said head being provided substantially centrally with an inturned cross-sectionally annular flange providing a discharge opening, and a closure removably engaging said flange.

In testimony whereof I affix my signature.
JOHN FRANKLIN MACINDOE.
